FASTENING INSERTING MACHINE

Fred N. La Chapelle, Beverly, Mass., assignor to
 United Shoe Machinery Corporation, Paterson,
 N. J., a Corporation of New Jersey

Application April 15, 1930. Serial No. 444,565

10 Claims. (Cl. 1—30)

This invention relates to fastening-inserting machines and is illustrated herein as embodied in a fibre peg inserting machine adapted for use in inserting pegs into shoe bottoms.

5 It is an object of the present invention to improve the operation of awl-feed fastening-inserting machines of the character, for example, used in heel-seat pegging. Such machines are commonly provided with a presser plate or abutment 10 against which the work piece is held by a suitable work support, the abutment being provided with a slot through which the awl passes in its work penetrating movement and along which it is moved during its work feeding movement. The 15 awls used in these machines vary in diameter according to the size and nature of the fastenings which are being inserted and in some instances are not heavy enough, at least if made of the steel commonly used for such parts, to stand 20 the strains to which they are subjected during the work feeding movement. These strains are increased at times, particularly when inserting fastenings in relatively soft stock, by the bulging of the work piece into the slot of the abutment 25 under pressure applied by the work support of the machine which presses the work forcibly against the abutment at the time of the awl penetrating movement and at the instant that each fastening is inserted. While the work support 30 is moved a short distance away from the abutment during the work feeding movement thereby relieving the pressure against the abutment, it happens at times that the stock is pressed up into the slot of the abutment at the time a fastening 35 is inserted and while the awl penetrates the work to make the hole for the succeeding fastening to such an extent that the bulge thus formed prevents the work piece from clearing the abutment properly during the subsequent feeding 40 movement of the awl. This, of course, increases the stresses and the consequent strain to which the awl is subjected during its work feeding movement.

In view of the foregoing a feature of the invention comprises a member illustrated herein as a hollow finger adjacent to and moving with the awl during its work feeding movement and constructed and arranged to engage and back up the awl, in effect stiffening the awl and thereby 45 relieving the awl of a large portion of the strain due to its work feeding movement. Preferably, moreover, and as illustrated herein, this member projects into the slot of the abutment in such a way as to prevent the work piece from bulging substantially into the slot or at least substan-

tially to reduce such bulging. This, of course, also reduces the stresses to which the awl is subjected.

When such a construction is used in a fibre fastening-inserting machine which inserts adhesive coated fastenings the member which backs up the awl can advantageously be used to transmit liquid used for moistening the adhesive coating of the fastenings. Thus in accordance with another feature of the invention the member of the illustrated machine which backs up the awl, and which as illustrated comprises a finger having an end substantially in engagement with the awl, is hollow and serves to conduct liquid to the awl from which it passes to the work piece thereby serving to moisten the dry adhesive coating of the fastenings.

With the above and other objects and features in view the invention will now be described with reference to the accompanying drawings and pointed out in the claims.

In the drawings,

Fig. 1 is a side elevation of a portion of a fastening-inserting machine embodying the present invention;

Fig. 2 is a front elevation, partly in section, of the lower portion of the head of the fastening-inserting machine of Fig. 1;

Fig. 3 is a horizontal section on the line III—III of Fig. 2;

Fig. 4 is a side elevation and Fig. 5 is a sectional view on the line V—V of Fig. 3 illustrating particularly the manner in which the awl of the machine is backed up during its work feeding movement; and

Fig. 6 is a detail side elevation of the member by which the awl of the machine is backed up.

The invention is illustrated as embodied in a machine of the type disclosed in Letters Patent of the United States No. 1,417,540, granted May 30, 1922 on an application filed in the name of Fred L. Mackenzie, the machine being provided, however, with a work support controlling mechanism including pawl and ratchet mechanism of the type illustrated in Figs. 23 and 24 of Letters Patent of the United States No. 1,686,808, granted October 9, 1928 on an application filed in the names of George Goddu and Fred L. Mackenzie. The illustrated machine is arranged to insert fibre fastenings instead of the metallic fastenings inserted by the machines of the patents just referred to and is accordingly provided with mechanism of the character shown in United States Letters Patent No. 1,849,253, granted March 15, 1932, upon an application filed in the name of Fred

N. La Chapelle, for supplying fibre pegs to its fastening inserted means. There are many of the parts of the machine which it is not necessary to describe in connection with the present invention 5 and for a full disclosure of such parts reference may be had to the above cited patents and application.

The illustrated machine is provided with a throat member 10 (Fig. 2) having a driver passage 10 through which reciprocates a driver 14. An awl 16 clamped to an awl bar 18 vertically reciprocable in an awl bar carrier 20 (Fig. 2) penetrates the work, illustrated as a shoe 26 having a sole 24, to form fastening-receiving openings therein 15 and is then moved to the left, as viewed in Figs. 2 and 5, by movement of the awl bar carrier 20 to feed the work, thereby bringing the hole formed by the awl in the work into alignment with the driver 14. At this time, of course, the throat member 20 10 is maintained to the rear of the awl so that there is no interference between the parts.

The work support 22 by which the shoe 26 is carried is maintained in its elevated position, as shown in Fig. 1, while the awl is given its work 25 penetrating movement, the sole 24 of the shoe 26 being at that time pressed forcibly against a substantially flat presser member or abutment 30 (Figs. 2 and 4) with which the machine is provided. During the feeding movement of the awl 30 16, however, the pressure is relieved in a well-known manner, in the illustrated machine by causing pawls 32 (Fig. 1) to lock a ratchet 34 against downward movement under influence of a heavy spring 36 after which toggle 38 is broken thereby lowering the horn post 40 and the work support 22. At the conclusion of the work feeding movement the toggle 38 is straightened and the pawls 32 withdrawn from the ratchet 34 so 35 that the spring 36 is effective to hold the horn post 40 of the work support 22 in a position to press the sole 24 of the shoe firmly against the abutment 30.

In order to prevent the awl from bending during the work feeding movement it is, in the illustrated machine, backed up by a rigid finger 44 45 secured to the awl bar carrier 20 by a screw and slot connection 46 (Figs. 2 and 3) and having an end 48 in supporting engagement with the awl 16. Thus any tendency of the awl to bend as the awl bar carrier is moved to the left by the awl bar 50 is resisted by the finger 44 and danger of breaking the awl is thereby obviated. It will be observed, moreover, that, as shown in Figs. 2 and 5, the end 48 of the finger 44 projects down into the slot 50 formed in the presser member 30 thereby preventing the sole 24 of the shoe from bulging upwardly into the slot under pressure applied by the work support 22 and eliminating such resistance to the feeding movement of the work 55 piece as would result from the bulging of the sole 24 of the shoe 26 into the slot 50.

The fibre fastenings 52 (Figs. 2 and 5) inserted by the illustrated machine are coated with dry glue which can be moistened as the fastenings are 60 inserted thereby cementing the fastenings into place. Accordingly the finger 48 is bored, as indicated at 54, 56, (Fig. 6) the bore 56 lining up with the passageway of a tube 58 driven into the finger 44, and connected by a rubber hose 70 60 with a source of supply of water. Thus the water is applied to the awl 16 and to the work piece adjacent to the awl by the finger 44, thus moistening the work piece and serving to soften the glue coating of the fastenings 52. A small 75 amount of water, moreover, may run from the

end of the finger 44 directly into the hole when the awl 16 is withdrawn from the work piece.

As pointed out above, in the illustrated machine the finger 44 performs three functions— 80 (1) backing up the awl during its feeding movement, (2) preventing the work piece from bulging into the slot of the abutment, and (3) serving as a conduit to supply liquid. It should be understood, however, that it is not essential under all circumstances that this member performs all of 85 these functions. It may, within the scope of the invention, perform any one or any two of them. It should be understood, moreover, that the invention is not to be regarded as limited to embodiment in a machine of the character illustrated 90 except to the extent required by the definitions of the claims.

Having thus described my invention what I claim as new and desire to secure by Letters Patent of the United States is:

1. A fastening-inserting machine having an awl constructed and arranged to make fastening-receiving holes in a work piece presented to the machine and to feed the work, a member adjacent to the work and moving with the awl during 100 its work feeding-movement comprising a finger the end of which engages and backs up the awl thereby relieving the awl of a large portion of the strain of its work-feeding movement, and means constructed and arranged to drive a fastening into 105 the work at the conclusion of the feeding movement.

2. A fastening-inserting machine having an awl carrier, an awl carried thereby and constructed and arranged to make fastening-receiving holes 110 in a work piece presented to the machine and to feed the work, a finger carried by the awl carrier adjacent to the work and moving with the awl during its work-feeding movement constructed and arranged to engage and back up the 115 awl thereby relieving the awl of a large portion of the strain of its work-feeding movement, and a driver arranged to insert a fastening into the work after the feeding movement has been completed.

3. A fastening-inserting machine having a slotted abutment, an awl constructed and arranged for movement through and along the slot of said abutment to form fastening-receiving holes in a work piece presented to said abutment 125 and to feed the work piece, a driver arranged to insert fastenings into the holes formed by the awl, a work support constructed and arranged to force the work piece against said abutment during the work-penetrating movement of the awl and during 130 the insertion of the fastenings, and a finger having a free end which backs up the awl and is positioned in the slot of the abutment to prevent the work piece from bulging substantially into the slot while the pressure is applied by the work 135 support at the time of the work-penetrating movement of the awl and of the insertion of the fastenings.

4. A fastening-inserting machine having a slotted abutment against which a work piece is 140 pressed while fastenings are inserted therein, an awl operating through the slot of the abutment to form fastening-receiving holes in the work piece and to feed the work piece, and a hollow member a portion of which is located in the slot 145 of the abutment constructed and arranged to prevent the work piece from bulging substantially into the slot, said member also serving to back up the awl thereby relieving it of the strain of its work feeding movement and serving as a 150

conduit to bring the liquid to the point of insertion of the fastenings.

5. A fastening-inserting machine having an awl constructed and arranged to form fastening-receiving holes in a work piece, a driver operated to insert fastenings in the holes formed by the awl, and means for supplying liquid to the surface of the awl from which the liquid is transferred to the work piece.

10 6. A fastening-inserting machine having an awl constructed and arranged to form fastening-receiving holes in a work piece, and a hollow finger constructed and arranged to back up the awl and having an end substantially in engagement with the awl thereby serving to conduct liquid to the awl.

7. A fastening-inserting machine having an awl constructed and arranged to form fastening-receiving holes in a work piece, and a hollow member backing up the awl, said member being connected with a source of supply of liquid and having an outlet closely adjacent to the awl whereby the liquid passes from the hollow member to the work piece.

25 8. A fastening-inserting machine having an awl constructed and arranged to form fastening-receiving holes in a work piece, a driver operated to insert in the holes fastenings the surfaces of which are of material which becomes adhesive under the action of a suitable solvent, and means for applying such solvent to the surface of the awl whereby the awl carries the solvent into the holes which it forms for the reception of the fastenings.

9. A fastening inserting machine having an awl constructed and arranged to make fastening receiving holes in and to feed a work piece, a rigid hollow finger terminating adjacent to the surface of the work piece in which fastenings are to be inserted and adjacent to the position occupied by the awl when it is thrust into the work piece to initiate work feeding movement thereof, means for moving said finger with the awl during the work feeding movement, and means for supplying liquid to the hollow finger whereby the liquid passes through the finger and is applied to the work piece at the points where the fastenings are to be inserted.

10. A fastening inserting machine having an awl carrier, an awl carried thereby and constructed and arranged to make fastening receiving holes in a work piece, a driver operated to insert fastenings in the awl holes, a rigid hollow finger terminating adjacent to the surface of the work piece and adjacent to the position occupied by the awl when it is thrust into the work piece to initiate the work feeding movement, means for moving the awl carrier when the awl has penetrated the work piece, thereby moving the awl to feed the work piece and moving the hollow finger with the awl, and means for supplying liquid to the finger whereby the liquid passes through the finger and is applied to the work piece at the points where the fastenings are to be inserted.
